TEETH SETTING MACHINE

Burr N. Engle and John B. Engle,
Los Angeles, Calif.Original application July 5, 1945, Serial No.
603,288, now Patent No. 2,441,403, dated May
11, 1948. Divided and this application March
23, 1948, Serial No. 16,516

3 Claims. (Cl. 76—58)

1

This application is a division of application Serial Number 603,288, filed July 5, 1945, which matured as Patent No. 2,441,403, dated May 11, 1948, entitled "Teeth Setter for Saws."

This invention relates to means and ways of setting saw teeth automatically without the necessity of making any adjustment after the machine is once set for operation upon a particular spaced set of teeth.

The means include a hammer element for bending every other tooth to one side of the blade and which is actuated by energy controlled by the saw teeth that have been set, thus, eliminating much auxiliary equipment which obviously would increase the cost of such a machine. The energy for working the setter may also be controlled by the teeth of the saw which have not been set.

One of the principal objects of this invention is to present a new and novel saw teeth setting machine that is simple and sturdy in construction, easy and simple to operate, and which is economical to make and manufacture.

Another object is to provide an automatic teeth setting machine in which the operator need only run the blade of the saw along a pair of guides in order to fully set the teeth, the teeth being set at a rapid pace and done in a perfect manner.

Other objects, advantages and features of this invention will appear from the accompanying drawings, the subjoined detailed description, the preamble of these specifications, and the appended claims.

Applicants are now about to illustrate and describe one of the forms of their invention in order to teach one how to make and use the same, but it is to be understood that the drawings and description thereof are not to limit the invention in any sense whatsoever except as limited by the expressions in the claims.

In the drawings:

Figure 1 is a plan view of the invention with parts thereof broken away.

Figure 2 is a cross sectional view of Fig. 1 with portions broken away.

The device comprises a machine having a heavy metal base 1 with an extended arm 2 for supporting a solenoid 3 over the site where the tooth setting is accomplished. The solenoid is wound as one coil with four taps therefrom, the coil taps each having an insulated conductor wire extending therefrom, for instance, like the ones indicated by the reference characters 4, 5, 6 and 7, and the ends of which connect with their respective switch contact points 8, 9, 10 and 11 shown

2

on the distributor switch body 12. The other end of the solenoid winding is connected by the wire 13 with the low side of a power supply switch 14. The switch 14 is preferably a single pole toggle switch connected to a source of suitable electric current by the two wire cord 15. One wire of the cord connects with the switch 14 and the other wire of the cord, the neutral wire, is connected to the base and thus grounded as shown at 16.

A spring-like pointer arm or bar 51 is pivoted to the base at 52 and the pivot pin is insulated from the bar 51 or/and the base 1 so that the pointer will not make electrical connection or contact with anything except certain bent teeth of the saw indicated at 53 and also of course the wires connected thereto. This arm 51 is connected to an insulated electrical conductor 54 which leads to the pivot connection 55 of the distributor switch 12; this pivot pin being insulated from the base and the contacts thereon and supporting the switch arm 56, as shown.

At the upper end of the pointer arm 51, but located and scribed upon the base of the machine, there is an arc 57 having a number of spaced divisional lines 58 numbered 4 to 8 and which represent the point measurements of the teeth in the various saws. The pointer is now shown as aligned with the divisional line 4 which indicates that the saw 53 is a four point saw, that is, four teeth to the inch. As shown in Fig. 2, the distal end of the pointer has an under pin 59 fixed thereto which is positioned so that it may engage any one of the holes 60 in the base 1 and thus prevent the arm 51 from moving when once set.

At the lower end of the pointer arm 51 there is a flexible electrical contact brush 61 which is positioned for making contact with any one of the teeth of the saw which happens to be bent downwardly. This type of control is workable when one tooth of the saw is bent into position by the hammer 33 to conform with the anvil 39 and thus make good electrical contact with the brush 61. Obviously, the teeth could be bent upwardly and the brush positioned to make contact with such teeth.

By the above arrangement, the plunger blow is regulated by the settings upon the contacts 8-11 and the plunger energized every time the brush 61 makes contact with a previously bent tooth as the saw is grounded onto the frame or base. Adjustable saw guides 38 are provided upon the base so that the saw teeth can be guided beneath the plunger in proper position.

A push button switch 14' is provided upon the

base and one side thereof is connected to an insulated conductor 14" that is connected with the wire 54 or the pointer arm 51 and the other side connected with or grounded to the base 1. The purpose of this push button is for independent operation of the plunger when the arm 51 is not in use, that is, by merely pressing the button switch 14', the plunger 33 is operated for setting teeth.

The following is claimed:

1. In a teeth setting device for saws, the device including a base with a top surface adapted to receive the blade of a saw, spaced apart saw guides on the base, an anvil intermediate the guides and aligned relative thereto, a solenoid supported by the base and positioned over the anvil, a plunger in the solenoid, the plunger being aligned with the anvil and adapted to strike it, a bar pivoted to the base, the bar having a contact brush at one end thereof which is adapted to make contact with bent teeth of the saw, means supplying electrical current to the solenoid with

said bar in series therewith so that the solenoid is energized only when the brush of the bar makes contact with a tooth of the saw to be set.

2. The device recited in claim 1 wherein the end opposite the brush of the bar has an insulated under pin and the base at this end of the bar has a scale with a plurality of stop holes which represent different tooth spacings of saws.

3. The device recited in claim 1 wherein the bar is elongated and pivoted to the base but insulated therefrom, the brush consisting of a thin metal strip.
